(57) **CLAIM**

The ornamental design for a gas emitter, as shown and described.

DESCRIPTION

FIG. 1 is a front perspective view of a gas emitter showing our new design.

FIG. 2 is rear perspective view of the gas emitter of FIG. 1

FIG. 3 is a top plan view of the gas emitter of FIG. 1

FIG. 4 is a bottom plan view of the gas emitter of FIG. 1

FIG. 5 is a front elevational view of the gas emitter of FIG. 1

FIG. 6 is a rear elevational view of the gas emitter of FIG. 1; and,

FIG. 7 is a side elevational view of the gas emitter of FIG. 1.

The broken lines represent environmental subject matter and

form no part of the claimed design.
